The ornamental design for a combined shoe bottom and periphery, as shown and described.

DESCRIPTION

FIG. 1 is a perspective view of the right, front and bottom of a combined shoe bottom and periphery showing my new design;

FIG. 2 is a right side elevational view thereof;

FIG. 3 is a bottom plan view thereof;

FIG. 4 is a left side elevational view thereof;

FIG. 5 is a front elevational view thereof; and,

FIG. 6 is a rear elevational view thereof.

The broken line showing the shoe upper in the Figures is for illustrative purposes only and forms no part of the claimed design.

The portion of FIG. 5 which is left unshaded is not part of the claimed design.
